TITLE BOARD

Lucien A. Dussol, Mount Marion, N. Y.

Application December 13, 1940, Serial No. 369,924

4 Claims. (Cl. 20—5)

This invention relates to imitation tile as made by shaping, and covering with enamel, lacquer or the like, the surface of a selected side of a wall board, to have the board at such side simulate an area of a wall actually expensively covered by a plurality of separate ceramic tile individually laid in tile cement and spaced from each other by cement lines located below the plane of the top flats of the tile-simulating elements.

This tile board, as it will be called, is commonly made of wall board in the form of fairly thin sheets of compressed material, usually fibre, as wood pulp, and is given the shaping above referred to by cutting into said surface intersecting grooves to subdivide the board into portions each of which is representative of a single ceramic tile.

After the board is thus shaped, the covering material is applied, in liquid form, and in two separate applications. The first of said applications, hereinafter called the tile finish, is laid all over the shaped surface, and the second of said applications, hereinafter called the cement finish, is laid as stripings in the bottoms of the grooves.

Tile board made as above is now a widely used article of manufacture, being especially valuable for store-fronts, show-cases, bath rooms, shower-tub stalls, and kitchens, to mention only some of its important fields of usefulness.

The makers of tile board, however, have long sought a solution of the serious problem of so cross-sectionally shaping the grooves that after drying and hardening of the tile finish, said tile finish will not be materially less resistant to water, steam and moisture at points along or adjacent to the lines of merger of the grooves with the main portions or top flats of the imitation tile units, than at said flats.

The previous inability adequately to solve this problem, I have found, has been due to universal adherence to the previous practice of cutting the grooves so that cross-sectionally they are shaped substantially like the lower half, or the major portion of the lower half, of the letter O, or of a square. As a consequence—in order to satisfy the demand of the market that the imitation tile units of the tile board have, by actual or apparent lie of their top flats well above the plane of the imitation cement lines between said units, a very close if not a perfect resemblance to actual ceramic tile individually laid by the expert tile setter—grooves made according to the practice just mentioned have had to be kept at their tops

to a width so limited as compared with their depth near their opposite sides that their side walls descend at a fairly steep angle. Because of this, the side walls of a groove have acted as spillways or slides down which the tile finish has slipped, in the unavoidable lapse of time between its application in liquid form and its setting to a point where such slip is entirely arrested. The result has been to reduce to a most undesirable extent the thickness of the tile finish along or adjacent to a line at or near the top of a groove side-wall. This localized thinning of the tile finish to less than the intended thickness thereof all over the tile board, and to less than the thickness of the tile finish over the top flats of the tile units and over the lower portions of the grooves, establishes zones of weakness in the tile finish so far as is concerned the function it must perform in acting as a protective barrier against penetration of water and steam therethrough and deterioratingly into the material of the wall board.

Previous workers in the art, in endeavors to prevent final loss of adequate thickness in the tile finish adjacent to the tops of the groove while nevertheless retaining a shape for the groove requiring fairly steep side walls therefor, have proposed, as remedies for this side-wall steepness, special localized formations for the side walls, such as rounded corners for the tops of the latter, auxiliary curvatures immediately above or below such rounded corners, and like expedients.

The real solution of the difficulty indicated above, I have found, by actual manufacture of tile board, is actually obtainable by employing what I call a compound groove, and one characterized by a V-shaped upper portion and a distinctly stepped-down minor lower portion, this latter portion having substantially vertical side walls.

The present invention will be clearly understood, and the advantages thereof appreciated, from the following description of a now preferred embodiment of the new groove as illustrated in the accompanying drawing.

In this drawing:

Fig. 1 shows a portion of a tile board made according to the invention, looking toward the top of the same, that is, toward the side of the board carrying the imitation tile units.

Fig. 2 is a sectional view, taken at right angles to the plane of the board, through one of the new grooves; this view being on an enlarged

scale, but with none of the coatings shown in Fig. 4 yet applied.

Fig. 3 is a view similar to and drawn on the same scale as Fig. 2, showing the sides of the V-shaped upper portion of the groove at a less angle to the plane of the board than in Fig. 2.

Fig. 4 is a view similar to and showing the same groove as in Fig. 2, but on a much enlarged scale, and also showing, in the case of a board treated with a preliminary priming coat, the dispositions of such coat and of the tile and cement finishes at completion of manufacture of the tile board.

The new groove of the present invention, as shown in Figs. 1, 2 and 4, is marked generally 10. Such groove, it will be noted, is a compound one, having an upper major V-shaped portion 11, and a lower minor distinctly stepped-down portion 12. The groove 10' of Fig. 3 is shown as differing from the groove 10 only in that the side-walls of the upper V-shaped portion 11 of the latter are inclined at angles of about 17° to the plane of the board while the side-walls of the upper V-shaped portion of the groove 10' of Fig. 3, this portion marked 11', are thus inclined at angles of about 12°; and in that while the bottom wall of the stepped-down portion 12 of the groove 10 is flat and horizontal, the same stepped-down portion of the groove 10', this portion marked 12', has a concavely-rounded bottom wall. These differences between the two grooves apparently are unimportant, so far as exhaustive tests have shown, in obtaining the advantages of the invention.

In preparation for the application of the tile and cement finishes, marked 14 and 15, respectively, in Fig. 4, the wall board, marked 16, after being grooved at a selected side thereof to subdivide that side into imitation tile units 17, is customarily at said side given a priming coat 18 of a highly pigmented varnish. The purpose of this priming coat 18 is to hide the color of the board, to fill in the minute porosities thereof, and to afford a nice smooth foundation for the tile finish 14.

While a most important function of the tile finish 14 is to give the imitation tile units the usually intended pure-white, or other desired coloration, and to impart to them the sheen and gloss typical of genuine ceramic tile, a vitally important purpose of this tile finish is also to provide, all over the whole side of the board carrying said units, a certainly dependable barrier against the penetration of moisture, steam and water into the material of the board.

In this last regard, I find that with a groove 10 or 10' shaped to have an upper V-shaped portion 11 or 11' as above described, and even with the legs 19 or 19' of such V having non-rounded mergers with the top flats of the imitation tile units 17, there is no really measurable thinning of the tile finish 14 either near said mergers or anywhere down along said legs 19 or 19'. I thus completely overcome the trouble thought to reside in the existence of a non-rounded corner at the meeting line of the side wall of a groove and the top flat of an imitation tile unit.

But this solution of the problem of providing an adequate thickness of the tile finish 14 at the lines of merger of the tops of the groove with the top flats of the imitation tile units and all the way down along the side walls of the groove, if these side walls were solely the V-legs 19 or 19', would not provide a tile board satisfactory to the trade from the standpoint of having the imitation tile

units 17 meet the requirement of having a very close resemblance to actually individually laid ceramic tile. The top flats of these units, for one thing, would not actually be, or at least not appear to be, high enough above the top surface of the cement finish lying in the groove bottoms.

This requirement, however, I fully meet by the groove of the present invention; due to the compound nature of the same as aforesaid, that is, due to the addition, below the V-legs 19 or 19', of the central minor stepped-down portion 12 or 12'. Such portion, it will be noted, is a comparatively narrow channel, and one of even less depth than width; this channel having side walls 20 which from tops to bottoms are straight and at right angles to the plane of the board, as in Fig. 2, or side walls 20' which from their tops to near their bottoms are straight and at right angles to the plane of the board, as in Fig. 3.

By the use of a compound groove of this kind, I actually lower the central longitudinal plane of the cement finish 15 to some extent below the bottoms of the V-legs 19 or 19', and at the same time I provide a shadow effect the visual result of which is apparently further to lower said plane so much below the top flats of the imitation tile units 17 that these units seem to stand out very boldly from said plane, while giving the illusion that they have marginal shapings very close indeed to those typical of actual ceramic tile.

This visual effect is apparently best obtained when the depth of the compound groove, as the groove 10 or 10', ranges from substantially .090" as a maximum to substantially .050" as a minimum (the present preference for such depth being .078"); when the width of said compound groove at its top is about five times its said depth; and when the bottom channel, as the channel 12 or 12', has at its top a width about twice its depth but only about one-sixth the top width of the compound groove. In order to obtain the advantages of the invention, the top width of the compound groove should, it is believed, be so related to the top width of the bottom channel that the former width is a multiple, within the range substantially of four times as a minimum and six times as a maximum, of the top width of the bottom channel. It will be noted that in Fig. 4 an attempt has been made, as far as the scale of the drawing will allow, to show now preferred relative dimensions as between the upper or V-shaped portion 11 and the lower portion or bottom channel 12 of the groove 10; and also to show, more or less diagrammatically, less thickness of the priming coat 18 and of the tile finish 14, over the top flats of the imitation tile units 17, than within the grooves, in view of the fact that, ordinarily, said coat 18, after drying and before application of the tile finish 14, is sanded, and the tile finish, after drying, is polished, with this sanding and polishing performed only at said top flats.

Considering now particularly the cement finish 15, which is always of a contrasting color or shade of color to that of the tile finish 14, the cement finish in practically every case being a pale gray or a grayish white, it will be noted that said cement finish, as finally set in Fig. 4, is almost entirely confined to the channel 12, having a main central body lying over the tile finish 14 where the latter extends along the bottom of the channel 12, but with this body along its opposite sides carrying wing-like upward extensions tapered upwardly as shown, said extensions marked 21. It will also be noted that the top surface of said

main body of the cement finish 15 is distinctly below the corners 22 (Figs. 2 and 4) formed between the tops of the side walls 20 of the channel 12 and the bottoms of the legs 19 defining the V-shaped upper main portion 11 of the groove, and that the tops of the wing-like extensions 21 are distinctly above said corners.

Such a final disposition of the cement finish in a groove 10 always results, I have found, when the cement finish is discharged from the trailing end of a striping gun, the output of which is regulated through controlled air pressure, with this gun drawn along and guided by the groove while being held in alignment with the groove and upwardly inclined at about a 45° angle away from and ahead of its trailing end, and while the cement finish is being discharged from the gun in a volume relative to its speed of travel along the groove sufficient to deposit in the latter the quantity of cement finish required, and at a low enough velocity to cause the cement finish to rise as high up along the sides of the groove as the points 23.

As shown very clearly in Fig. 4, the final disposition of the cement finish is not only such that its extensions 21 rise up above the corners 22, as already pointed out, but these extensions are so built up on the tile finish 14, in the vicinity of said corners, that there the combined thicknesses of the tile and cement finishes is at least equal to the thickness of the tile finish alone elsewhere over the tile board.

What the present invention does, really, is to provide, for use in making a tile board, a novel groove which from its very nature, transfers a necessarily present corner from a trouble-making location, to a new and innocuous one, so far as is concerned the previous difficulty in endeavoring to employ a layer of tile finish 14, evenly distributed in liquid form all over the board, for establishing a barrier against the penetration into the board of moisture, steam and water. Whereas the old trouble-making corner was at the very top of the groove, out of reach of assistance by the cement finish 15 to the tile finish 14 in the work to be done by the latter in establishing said barrier, said corner is by the present invention lowered far enough down in the groove to allow the cement finish, applied as a striping at the depressed location at which it must be applied, to act conjointly with the tile finish, where the latter may be thinned in the vicinity of said corner, in establishing the required thickness of the barrier in said vicinity.

That the cement finish 15, after being deposited up along the sides of a groove as above described, always sets in such manner that the extensions 21 are finally present substantially as shown in Fig. 4, is, I believe, due in part to what in physics is known as the meniscus effect, in part to the relatively high viscosity of tile and cement finishes (liquids such as lacquers, enamels, plastics, and the like), and in part to the tendency of a later applied coat of such a liquid to coalesce with or strongly cling to a previously applied coat of a like liquid, when the former coat is applied before the latter coat, although dried somewhat, has fully set. In this latter connection, it should be noted that the now preferred practice in the art is to use a lacquer, enamel or plastic of the same kind, and of the same type or composition (except for coloring matter), for both the tile and

cement finishes; and to apply the stripings for the cement finish before a full setting (usually by baking) of the tile finish.

I claim:

1. A tile board having intersecting grooves in one of its sides which subdivide the latter into imitation tile units having top flats, each groove comprised of an upper V-shaped portion and a lower minor central portion constituting a bottom channel having side walls which at their tops have a substantially sharp-corner joinder with the bottoms of the side walls of said V-shaped portion, the side walls of said V-shaped portion having like oblique inclinations to the plane of the board, such inclination being within the range of approximately 12° to said plane, as a minimum, and approximately 17° to said plane, as a maximum, and the top width of said V-shaped portion being a multiple, within the range substantially of four times as a minimum and six times as a maximum, of the top width of said bottom channel.

2. A tile board having intersecting grooves in one of its sides which subdivide the latter into imitation tile units having flat tops, each groove comprised of an upper V-shaped portion and a lower minor central portion constituting a bottom channel; the side walls of said V-shaped portion, hereinafter called the V-legs, having like oblique inclinations to the plane of the board, such inclination being within the range of approximately 12° to said plane, as a minimum, and approximately 17° to said plane, as maximum, and the top width of said V-shaped portion being a multiple, within the range substantially of four times as a minimum and six times as a maximum, of the top width of said bottom channel; said V-legs being substantially flat all the way down along the same substantially to the tops of the side walls of said bottom channel, these last-named walls hereinafter called the lower side-walls, said lower side-walls from near their tops to near their bottoms having general lines of extension which are considerably closer to a 90° angle to the plane of the board than to a 35° such angle, the hereinabove specified angles being such that the general line of approach of each V-leg to the general line of extension of the adjacent lower side-wall defines an angle which is at least three times greater than the angle of upward approach of said V-leg to a line joining the flat tops of the tile units at opposite sides of the groove.

3. A tile board as in claim 1, in which the side walls of said V-shaped portion have a sharp-corner joinder with the top flats of the imitation tile units, but a corner defining an angle less than one-third that defined by the corner first-mentioned.

4. A tile board as in claim 2, in which said side of the board is covered all over with a tile finish, and in which the bottoms of the grooves are covered with a cement finish overlying the tile finish in said groove bottoms, the cement finish being in the form of a substantially U-shaped film the upper ends of the legs of which U are located, with said side of the board uppermost, above the level intermediate the top and bottom of the groove marked by the point of intersection of the general line of approach of a V-leg toward the adjacent lower side-wall, and the general line of extension of said side-wall.

LUCIEN A. DUSSOL.
